UNITED STATES PATENT OFFICE.

THOMAS HENRY SMEDLEY, OF LONG EATON, ENGLAND, ASSIGNOR TO RICHMOND
LACE WORKS, OF ALTON, RHODE ISLAND, A CORPORATION OF MAINE.

DESIGN FOR LACE.

Application filed November 29, 1922. Serial No. 4,450 $\frac{1}{2}$. Term of patent 3 $\frac{1}{2}$ years.

To all whom it may concern:

Be it known that I, THOMAS H. SMEDLEY, a subject of George V, King of England, residing at Long Eaton, shire of Derby, England, have invented a new, original, and ornamental Design for Lace, of which the following is a specification, reference being had to the accompanying drawing, forming part thereof.

The figure is a face view of lace showing my new design.

I claim:—

The ornamental design for lace, as shown.
THOMAS HENRY SMEDLEY.
